CLAIM

The ornamental design for a multi-function grill, as shown and described.

DESCRIPTION

FIG. 1 is a perspective view of a multi-function grill showing my new design;

FIG. 2 is a front elevational view thereof;

FIG. 3 is a rear elevational view thereof;

FIG. 4 is a right side view thereof;

FIG. 5 is a left side view thereof;

FIG. 6 is a top plan view thereof; and,

FIG. 7 is a bottom plan view thereof.

The broken line showing is for the purpose of illustrating portions of the multi-function grill which form no part of the claimed design.

1 Claim, 7 Drawing Sheets
